FIG. 1

Des. 194,958

PAGE 2

FIG. 2

FIG. 3

FIG. 1 is a perspective view of a combined motion picture projector and carrying case therefor with the case closed, taken from the front and one side, and showing our new design;

FIG. 2 is a perspective view corresponding to FIG. 1 and showing the case open for use of the projector; and

FIG. 3 is a perspective view thereof with the case closed, taken from the rear and the other side.

The bottom of the combined motion picture projector and carrying case therefor is plain and forms no part of the novel design.

We claim:

The ornamental design for a motion picture projector and carrying case, as shown and described.
